(57) **CLAIM**

The ornamental design for a can opener, as shown and described.

DESCRIPTION

FIG. 1 is a bottom perspective view of a can opener showing the present invention;

FIG. 2 is a top perspective view of the can opener of FIG. 1; FIG. 3 is a side elevation view of the can opener of FIG. 1; FIG. 4 is an opposite side elevation view of the can opener of FIG. 1;

FIG. 5 is a top plan view of the can opener of FIG. 1; FIG. 6 is a bottom plan view of the can opener of FIG. 1; FIG. 7 is an end view of the can opener of FIG. 1; and, FIG. 8 is an opposite end view of the can opener of FIG. 1. The broken lines in the drawings illustrate surface details which form no part of the claimed design.
